UNITED STATES PATENT OFFICE.

CHARLES WHITFIELD, OF KETTERING, ENGLAND.

PROCESS OF MAKING GAS.

SPECIFICATION forming part of Letters Patent No. 650,698, dated May 29, 1900.

Original application filed December 30, 1897, Serial No. 664,777. Divided and this application filed November 9, 1899. Serial No. 736,392. (No specimens.)

To all whom it may concern:

Be it known that I, CHARLES WHITFIELD, a subject of the Queen of Great Britain and Ireland, residing at Kettering, in the county 5 of Northampton, England, have invented Improvements in Processes of Making Gas, of which the following is a specification.

This invention has for its object the more complete conversion of solid hydrocarbon 10 compounds into the gaseous state than has been possible by the means heretofore in use; and the invention is designed for use with that class of apparatus which is employed for the generation of what are commonly known 15 as "producer-gas" and "water-gas."

It is well known that when carbonaceous fuel is burned with oxygen carbonic acid is produced and that when this compound is passed through a mass of incandescent carbon it is 20 converted into carbonic oxid. When atmospheric air is used for supplying the oxygen for the combustion of the carbonaceous fuel and steam is added, the oxygen and hydrogen of which the latter is composed become dis- 25 sociated, the oxygen thus liberated combining with some of the carbon, forming an additional supply of carbonic oxid. This additional supply of carbonic oxid and the dis- 30 sociated hydrogen enrich the first products and reduce the percentage of diluent nitrogen in the resultant compound. Owing, however, to the cooling effect of the steam and carbonic acid on the incandescent fuel and to the fact 35 that the conversion of carbonic acid into car- bonic oxid can only be completely effected at a temperature of about 1,000° Fahrenheit, the amount of steam that can be treated in this way is limited by the amount of sensible heat (produced by the initial combination of the 40 oxygen of the atmosphere with the carbonaceous fuel on the grate or near the twyvers) which is available above that temperature. Also, as the heavier hydrocarbons are only converted into fixed gases when raised to a 45 temperature somewhat above 1,000° Fahrenheit in contact with a further supply of oxygen or hydrogen, it becomes necessary to heat the vapors which are given off when the fuel is first placed in the generator or producer to 50 or above that temperature. Now my invention has reference to a method whereby vap-

orized or distilled hydrocarbons produced at the top of the generator or producer are combined with a proper quantity of oxygen and hydrogen and are raised to a sufficiently-high 55 temperature to convert them into permanent gases.

The process consists, first, in raising the fuel to a high temperature at or near the bottom of the generator or producer by forcing 60 air, either at ordinary temperatures or heated in any suitable way, through the grate or twyvers; secondly, in injecting into the fuel, at a point above the zone of combustion where the said fuel is in a state of incandescence 65 and where its temperature is sufficiently high, as much steam as the heated fuel will decompose in view of the other work to be accomplished, and, thirdly, in causing the said steam to convey the condensable and distillation products of the fuel into the said incandescent fuel before the gaseous products pass 70 off through the main outlet.

In order to carry out the above-described method, I employ apparatus of the kind described in another application for Letters Patent filed by me, dated December 30, 1897, Serial No. 664,777, of which this application is a division, and such as I shall now describe with reference to the accompanying draw- 75 80 ings, in which—

Figure 1 represents a plan of the generator or producer. Figs. 2 and 3 are vertical sections taken on the lines X X and Y Y, respectively, of Fig. 1; and Fig. 4 is a horizontal section taken on the line Z Z of Fig. 3. Figs. 5 and 6 are similar views to Figs. 3 and 4, respectively, showing a modified construc- 85 tion.

At some distance—say one or two feet— 90 above the grate or bottom A in the arrangement shown in Figs. 1 to 4, inclusive, there is provided a belt B, that extends more or less around the generator and is connected by openings C with the interior of the fuel-space 95 just above the zone of combustion. The belt B is connected by a casing B' and a pipe or conduit D with the top of the generator, where the fuel is admitted through a hopper F. Into the casing B' projects a steam-nozzle E in such 100 a manner that the steam issuing from the nozzle will induce a current of gas to flow.

from the upper part of the generator to the belt, so that the steam which is to be decomposed carries with it the volatile compounds evaporated or distilled from the fuel at the 5 said upper part of the generator. The steam-jet may be regulated by hand, or, if preferred, automatically, by any suitable arrangement. The action of the steam-jet causes the vapors from the fuel in the upper part of the generator to pass in such a direction and manner as to render it almost impossible for any of the 10 heavier vaporized hydrocarbon compounds to escape to the outlet G, which is placed at some distance—say two or three feet—from 15 the top of the generator, without first passing through a mass of incandescent fuel at H, and there becoming decomposed or otherwise fixed.

I is an opening for the admission of air into 20 the closed ash-pit below the fire-bars A from a blowing engine or fan.

J is a sight-hole for viewing the interior of the generator or producer when the same is at work, and K is an opening through which 25 the generator or producer can be cleaned out when necessary. This opening is kept normally closed by a retort-lid P or other suitable air-tight door.

Instead of using a belt B, I sometimes, as 30 shown in Figs. 5 and 6, connect the lower end of the downtake pipe or conduit D and branch pipe B' by a conical nozzle B² to an opening or passage L, which leads the steam and the volatile compounds from the upper 35 part of the generator into the fuel at a point just above the zone of combustion.

It will now be understood that if air be passed through the mass of combustible fuel at the lower part M of the generator or producer it will raise the fuel to a high temperature, and thereby produce combustion in the lower part of the fuel and produce and maintain incandescence in a mass of fuel at the part H above the zone of combustion, and 45 that the green fuel at the upper part will be comparatively cool, but kept hot enough by the transmission of heat from the incandescent fuel below to give off volatile hydrocarbon compounds, which will be continually 50 drawn away through the pipe or conduit D by the steam-jet E and delivered along with the steam into the incandescent fuel at the part H of the generator or producer just above the zone of combustion. These volatile 55 hydrocarbon compounds and the steam are decomposed by the said incandescent fuel and pass off along with the carbonic acid produced by the combustion of the fuel at the lower part of the furnace through the outlet 60 G. It will thus be seen that the process hereinbefore set forth is a continuous one.

The distance between the openings C, through which the steam and hydrocarbon vapors are admitted to the generator, and the outlet G, provided for conveying the gas to the holder or to the point where it is to be employed, may vary. The less this distance is

the freer will the gaseous products escaping from the outlet G be from tar and condensable products. I have obtained very satisfactory results with a producer having a height of about twelve feet from the floor-level to the top of the fuel-chamber and an internal diameter of about two feet, the inlet or inlets C or L being about three feet above the 70 grate A, the outlet G about eight feet above the grate, the pressure of the air supplied to the ash-pit being about equal to seven or eight inches of water, and the pressure of steam admitted by the nozzle E being about 75 seventy pounds per inch. With this data about one hundred and eighty pounds of coal can be burned per hour, yielding about thirteen thousand cubic feet of gas having a high 80 calorific power.

I 85 The feeding of the fuel may be effected by hand or by any suitable automatically-acting apparatus, and where automatic apparatus is not employed the clinkering and pokerizing may be effected as in other generators or producers.

By carrying out the process as above described it is possible to utilize the heat produced by the initial combustion of a given weight of fuel, first, for the production of 90 carbonic acid, and, secondly, for the decomposition of the greatest possible volume of steam and the fixing of all the volatile hydrocarbons, whereby a compound containing the 95 smallest percentage of diluent nitrogen, with a high percentage of carbonic acid, hydrogen, and the lighter hydrocarbons, is obtained, the volatile hydrocarbons being made to enrich what would be under ordinary circumstances only common producer-gas. Also the process 100 enables cheap bituminous qualities of coal to be economically and advantageously converted into combustible gas in gas-producer 105 in lieu of the more expensive anthracite and hard qualities of coal which it has heretofore 110 been necessary to use, and not only so, but enables a gas having a higher calorific power 115 to be obtained than can be obtained in the usual way from such expensive fuels.

I am aware that it has heretofore been proposed to introduce volatile compounds generated at the upper part of a gas-producer, with or without steam, into the ash-pit or into the zone of combustion; but such process, which I do not claim, differs, essentially, from mine, inasmuch as the resulting gas is altogether of a different and inferior quality to that obtained by my process.

What I claim is—

1. The process of producing combustible 125 gas consisting in passing air only through the lower part of a mass of combustible fuel so as to raise the fuel to a high temperature, and thereby to produce combustion in the lower part of the fuel, and to produce and maintain incandescence in a mass of fuel above the zone of combustion, feeding green fuel on the top of the mass of fuel, injecting hydrocarbons distilled from said green fuel into the 130

mass of incandescent fuel above the zone of combustion produced by the air, and withdrawing the resulting gaseous products from the mass of fuel at a point below the green fuel at the top of the mass and the point where said hydrocarbons are injected, the mass of fuel above said zone of combustion being maintained at a gradually-decreasing temperature from this part to the top of said fuel.

10 2. The process of producing combustible gas consisting in passing air through the lower part of a mass of combustible fuel so as to raise the fuel to a high temperature, and thereby to produce combustion in the lower part 15 of the fuel, and to produce and maintain incandescence in a mass of fuel above the zone of combustion, feeding green fuel on the top of the mass of fuel, withdrawing volatile compounds and products of distillation given off 20 from the green fuel at the upper part of said mass and injecting the same into the mass of incandescent fuel above the zone of combustion produced by the air, and leading off the gaseous products at a point between the zone 25 of combustion and the upper part of the mass of fuel, the mass of fuel above said zone of combustion being maintained at a gradually-decreasing temperature from this part to the top of said fuel, substantially as described.

30 3. The process of producing combustible gas consisting in passing air through the lower

part of a mass of combustible fuel so as to raise the fuel to a high temperature, and thereby to produce combustion in the lower part of the fuel, and to produce and maintain incandescence in a mass of fuel above the zone of combustion, feeding green fuel on the top of the mass of fuel, withdrawing volatile compounds and products of distillation given off from the green fuel at the upper part of said mass and injecting the same by means of steam into the mass of incandescent fuel at a point above the zone of combustion produced by the air, and leading off the products of combustion of the fuel and the products of decomposition of the steam and volatile compounds and distillation products before they reach the upper part of the mass of green fuel from which said volatile compounds and distillation products are given off, the mass of fuel above said zone of combustion being maintained at a gradually-decreasing temperature from this part to the top of said fuel, substantially as described. 35 40 45 50

Signed at Northampton, in the county of Northampton, in England, this 25th day of October, 1899.

CHARLES WHITFIELD.
